GERMICIDE

Spencer J. Currie, Harnett County, N. C.

No Drawing. Application May 22, 1935,
Serial No. 22,881

3 Claims. (Cl. 167—65)

This invention relates to germicides.

Among the objects of the present invention is the production of germicides having positive germicidal action, pronounced penetrating characteristics, whereby they enter below the immediate surface of the skin, and which also form protective coatings over the injured portion of the skin being subjected to their action.

Further objects and advantages will appear from the more detailed description given below, it being understood however that this more detailed description is given by way of illustration and explanation only, and not by way of limitation, since various changes therein may be made therein by those skilled in the art without departing from the scope and spirit of the present invention.

In accordance with the present invention, a germicide is utilized by employing an aqueous solution of a substance having germicidal action, in combination with a volatile organic solvent, which is compatible with the aqueous solution of the germicidal agent. While the germicidal agents employed are preferably those which are soluble in water, germicidal agents may be employed which form dispersions rather than solutions.

The germicidal agents preferably employed in accordance with the present invention are tri-phenyl-methane dyestuffs which exhibit germicidal action. The rosaniline series of dyestuffs are particularly valuable in this connection, and will be illustrated below by crystal violet.

The volatile organic solvents employed are best illustrated by the group of glycol ethers, and particularly the ethers of the polyethylene glycols. Monoethyl ether of diethylene glycol is particularly effective and valuable in this connection, and will particularly illustrate the volatile organic solvents employed.

In producing the germicidal compositions in accordance with the present invention, any method of combining the ingredients may be employed, but the following is particularly desirable. 1 gram of crystal violet is dissolved in each 20 c. c. of monoethyl ether-diethylene glycol, which is to be employed. It is found that on solution of the crystal violet in the glycol ether, the solution warms materially. There is, therefore, evidence of chemical action, as indicated by this warming or rise in temperature during the solution of the crystal violet in the monoethyl ether of diethylene glycol. The solution desirably is permitted to cool, as by standing, for one-half

hour, and then for each 20 c. c. of the glycol ether present, 80 c. c. of water is intermixed.

This crystal violet-glycol ether aqueous composition is particularly effective as a germicide. It exhibits penetrating powers, that is, instead of merely remaining on the surface of the skin as aqueous solutions do, due to the presence of the glycol ether, the composition has remarkable penetrating powers. It has also been found that the germicidal action of crystal violet and its equivalent materials, is enhanced very materially by the glycol ether, particularly the monoethyl ether of diethylene glycol. A further important feature is that a composition of the character set forth above forms some kind of a protective coating over the surface of the injured or wounded skin to which it may be applied. Exactly what this protective coating is due to is not known. But it is not obtained unless the glycol ether is utilized in the composition with the crystal violet, or related dyestuff. These features of penetrating power, enhanced germicidal action, and protective coating are of great importance in connection with the present invention.

The proportion of ingredients may vary within rather wide limits. The amount of germicidal agent, such as crystal violet, present should be sufficient to give the desired germicidal action for any particular purpose. For general use, an amount of the order set forth above is desirable. The amount of glycol ether present in the composition may vary, as indicated. It is found, however, that particularly valuable results are obtained by having 20% of the monoethyl ether of diethylene glycol present in the composition, particularly with respect to the formation of the protective coating referred to above. Beyond 20%, the amount of the glycol ether may tend to give some irritating effect. Below 10%, the protective coating obtained is not as good as that with a 20% composition. While, therefore, the amounts of the glycol ether present in the composition may vary materially, unique results are obtained by utilizing a 20% composition.

The glycol ethers illustrated by the monoethyl ether of diethylene glycol is particularly emphasized as a valuable volatile organic solvent for utilization in this connection, particularly because of the several properties referred to above, and also because of its compatibility with the aqueous solutions. This is true generally of the class of glycol ethers of which monoethyl ether of diethylene glycol is representative. The other glycol ethers may be employed, and amongst other volatile organic solvents to which reference

may be made are the ethanolamines, particularly triethanolamine, the class of glycols and polyglycols, isopropyl alcohol, etc.

The pronounced germicidal action of compositions produced in accordance with the present invention may be particularly illustrated by comparing such action of the crystal violet-monoethyl ether of diethylene glycol composition referred to above with merthiolate, and their relative effects on staphylococcus albus. Comparative tests have indicated that the germicidal action of the crystal violet composition of the present invention is more than 1000 times as great as that of merthiolate, as exemplified by the fact that while merthiolate inhibited incubation of the staphylococcus albus in dilutions of 1 to 1000 for 3 days, the crystal violet combination of the present invention inhibited the same coccus for the same period of time in a dilution of 1 to 1,000,000. In the utilization of the germicidal compositions of the present invention, the protective coating referred to above does not form on healthy skin, but only on the surface of the skin exhibiting wounds or infected areas. It is possible that some combination with the serious discharge, or with the blood from the wound or infected area may take place. The action of the germicidal

composition on healthy skin is to leave a deep violet stain, which gradually disappears. Whether or not the explanation given above for the appearance of the protective coating is correct is immaterial, since the protective coating does actually form over the wounded or injured or infected portion of the skin, and is one of the features particularly emphasized in connection with the present invention.

Having thus set forth my invention, I claim: 10

1. A germicide for topical application containing an aqueous solution of a triphenyl methane dyestuff having germicidal properties, and a sufficient amount of a lower alkyl ether of diethylene glycol compatible with water to give 15 the composition substantial penetration.

2. A germicide for topical application containing an aqueous solution of a rosaniline dyestuff germicide, and a lower alkyl ether of diethylene glycol in an amount sufficient to give the composition substantial penetrating properties. 20

3. A germicide for topical application containing an aqueous solution of crystal violet, and from 10 to 20% of the monoethyl ether of diethylene glycol.

SPENCER J. CURRIE.
